BEVERAGE DISPENSER

Clare E. Hodgman, Mamaroneck, N.Y., assignor to The Coca-Cola Company, Atlanta, Ga., a corporation of Delaware

Filed Oct. 23, 1959, Ser. No. 58,037

Term of patent 14 years

(Cl. D2—3)

The essential features of the design are shown in full lines.

I claim:

The ornamental design for a beverage dispenser, as shown and described.
